UNITED STATES PATENT OFFICE.

FRANK W. BEARDSLEY, OF NEW YORK, N. Y., ASSIGNOR TO SEABOARD SPECIALTY CORPORATION, OF NEW YORK, N. Y., A CORPORATION OF NEW YORK.

DISH-WASHING MACHINE.

1,150,924.

Specification of Letters Patent. Patented Aug. 24, 1915.

Application filed October 4, 1909, Serial No. 520,983. Renewed January 21, 1915. Serial No. 3,632.

To all whom it may concern:

Be it known that I, FRANK W. BEARDSLEY, a citizen of the United States, and a resident of New York, Richmond borough, in the county of Richmond and State of New York, have invented certain new and useful Improvements in Dish-Washing Machines, which improvements are fully set forth in the following specification.

10 This invention relates to improvements in constructions of that class commonly known as dish-washing machines, the same being availed of for subjecting dishes and analogous utensils to a cleansing operation.

15 The object of this invention is to provide a machine of the character above indicated which shall be simple and comparatively inexpensive as regards construction; durable, efficient and reliable in practical service; 20 convenient in its application to practical purposes; and which shall possess certain well-defined advantages over prior analogous constructions.

25 The invention consists in the novel combinations, parts and details whereby, together with the novel disposition and relative arrangement of said parts, the attainment of the foregoing object is rendered practicable, all of which will be more 30 specifically referred to hereinafter and set forth in the appended claims.

35 The invention is clearly illustrated in the accompanying drawings, wherein similar reference-numerals denote corresponding parts throughout the several views, as to which:

Figure 1 is a plan view of a dish-washing machine embodying my said improvements. Fig. 2 is a vertical section of same, as along 40 the line $x-x$ of Fig. 1. Fig. 3 is a side elevation of a fragment thereof. Fig. 4 is a transverse section, as along the line $y-y$ of Fig. 3. Fig. 5 is an enlarged detail view showing, in front elevation and detached, 45 one of the pendent dish-containers made use of. Fig. 6 is a central, vertical, transverse section of the construction shown in Fig. 5, and Fig. 7 is a plan view thereof.

In carrying out my invention, reference 50 being had to the accompanying drawings, I make use of a main tank 2, adapted to contain a suitable quantity of cleansing fluid, and preferably divided, as by means of a

transverse partition wall 2', into a washing compartment 2'' and a rinsing compartment 55 2'''. The washing compartment 2'' is also provided, by preference, with an overflow pipe 3''', to the end that cleansing fluid may be continuously introduced therein. I further make use of a flexible, endless 60 conveyer to which there is pivotally attached a dish-container, or a plurality thereof, said conveyer being disposed and adapted to carry said dish-container, or dish-containers, thereto pivotally attached, into and out of 65 the bath of cleansing fluid contained in said tank. Specifically, I make use of opposite, endless sprocket-chains, 3, 3', suitably spaced apart, and operating in parallel vertical planes, the former on a system of 70 sprocket-wheels 3'', and the latter on a like system of sprocket-wheels 3'''. The sprocket-wheels 3'' are mounted, respectively, on spindles 4, rotating in bracket-bearings 4', attached to the tank 2, at one 75 side thereof, and the sprocket-wheels 3''' are correspondingly mounted on similar spindles 4'', rotating in similar bearings 4''', attached to said tank at the opposite side thereof.

80 It is essential that the chains 3, 3', move in unison in the practical operation of the machine, and this notwithstanding each operates on its own distinct system of sprocket-wheels. Therefore, I provide, for the purpose stated, positive driving mechanism, which is here shown as comprising a main shaft 5, rotatably arranged transversely of the tank 2, at the forward end thereof, considered with respect to the direction of 85 movement of the general rotating parts of the machine, and as in bearings 5', attached to said tank exteriorly thereof; sprocket-wheels 5'', 5''', firmly mounted on said main shaft; sprocket-wheels 6, 7, firmly mounted, the 90 former on one of the spindles 4, outside of the tank 2, said spindle being extended to this end, outwardly through and somewhat beyond the adjacent side-wall of said tank, and the latter correspondingly mounted on 95 one of the spindles 4'', extended, to this end, outwardly through and somewhat beyond the opposite side-wall of said tank, and being, by preference, that one of the system of spindles 4'' which is arranged in axial 100 alignment with that one of the spindles 4, on

which the sprocket-wheel 6 is mounted; and transmission chains 6', 7', operating, the former one the sprocket-wheels 5'', 6; and the latter on the sprocket-wheels 5'', 7, all 5 as clearly shown in the drawings. Hence, upon shaft 5 being rotated, as in the direction indicated by the arrow 7'', in Fig. 5, and as through the medium of a pulley 7''', firmly mounted thereon, and in connection, 10 as through the medium of a belt 8, with any appropriate source of power, its motion will be transmitted to the respective chains 3, 3', through the medium of the driving-mechanism parts above enumerated, to continuously move the same in unison into and out 15 of the washing compartment 2'' and into and out of the rinsing compartment 2'''. In connection with said conveyer I further make use of a novel dish-container, adapted to receive and contain dishes varying quite 20 widely as to size, general contour or depth, the same being pivotally attached to said conveyer and depending, by its own gravity and at all times, therefrom. Specifically, 25 the dish-container aforesaid comprises a stirrup 8', pivotally attached to the chains 3, 3', respectively, as at the points 9, 9', and being thus situated between the same and pendulously depending therefrom; and an 30 openwork basket, the latter rockably attached to said stirrup.

The basket aforesaid comprises a vertical back 8'', which is provided at its upper, rear edge-portion, considered with reference 35 to the discharge end of said basket, with a hook 8''', the purpose of which will be made more apparent hereinafter; a front wall 9'', attached to or formed integral with, said back, and flared upwardly and away therefrom; and an end-segment 9''', connecting said back and said front wall, at the rear edge-portion thereof, all as clearly indicated 40 in Figs. 5, 6 and 7 of the drawings.

The basket aforesaid is preferably 45 formed from sheet metal of appropriate thickness, its back, front wall, end-segment and bottom, being, respectively, provided with a multiplicity of suitable openings, as 50 to the end that the fluid used in the tank 2 may surge freely, in various directions, through the same, in the practical operation 55 of the machine as a whole.

The back 8'' is projected downwardly at its forward, lower edge-portion, to form a leg 10', terminating in a forwardly projecting foot 10''; and the stirrup 8' has an arm 11, arranged at right angles thereto along its bottom, and to the front end of which arm the basket aforesaid is pivotally attached, as by means of a pivot 11', which passes through the leg 10' and the arm 11, the front end of the latter lapping alongside of said leg to permit this mode of assembling the parts in question, said stirrup and

the arm 11 constituting a general frame on 65 which the dish-basket aforesaid is mounted. The stirrup 8' is also provided at its top with a rearwardly projecting guide-arm 12, having a curvature concentric with the axis of movement of the basket aforesaid with 70 respect to said stirrup, or, in other words, the pivot 11'; and the hook 8''', hereinbefore mentioned, takes freely over, and has a more or less sliding engagement with, said guide-arm, the latter accordingly serving as 75 a guide for the upper portion of the basket aforesaid in its to and fro rocking movement, as on the pivot 11'.

It will be noted that the foot 10' and arm 11 coöperate to form a jointed counter-brace, 80 which in turn coöperates with a vertical guide, consisting of opposite, upright guide-members 12', 12'', arranged at opposite sides of the course of movement of the conveyer aforesaid, and at a suitable point therealong. The said guide-members now under consideration are, in this instance, disposed interiorly of the tank 2, at the rear end thereof, and are respectively held in position by means of suitable braces, 13, attached 85 thereto and extended therefrom and attached to the adjacent walls of said tank, as indicated in the drawings.

The function of the guide just referred to is to temporarily check any tendency of the 95 dish-container aforesaid, to pendulous movement with respect to the conveyer aforesaid, and during the dumping or forwardly rocking action of said basket, as on the pivot 11'; and to facilitate the performance of this function, by said guide, I arrange the upright, constituent members thereof at suitable points to insure a more or less sliding engagement thereof, respectively, by the opposite ends of the counter-brace above referred to, and during an ample period within which the dumping 100 action of the basket aforesaid may take place.

Specifically, I purpose to provide the 110 guide members 12', 12'', the one with a longitudinal channel 13', and the other with a corresponding channel 13'', and into which channels, each being suitably flared at one or both of its ends, the opposite ends of said 115 counter-brace may directly enter, where a sliding friction between the counter-brace and said guide-members is not objectionable. I prefer, however, to provide rollers 14, 14', at the opposite ends of the counter-brace aforesaid, which rollers may enter and roll along the channels 13', 13'', respectively, thereby minimizing the friction between 120 said counter-brace and the members 12', 12'', in the practical operation of the machine 125 as a whole.

It is essential that means be provided whereby, as the dish-container moves along

with the conveyer, and during more or less of the time that said counter-brace is in engagement with said guide, the basket aforesaid is caused automatically to undergo 5 its dumping or forwardly rocking action; and to this end I provide the member 12' with a cam-face 14", located in the line of movement, with the dish-carrier, of the foot 10", or the roller 14' carried thereby, and 10 accordingly within the channel of said member. Hence, as the conveyer moves along, the foot 10", or its roller 14', is brought into engagement with said cam-face, and to escape the same, as the conveyer continues to 15 move along, the foot 10" directly, or indirectly through the medium of the roller carried thereby, is caused, by said cam-face, to rock downwardly on the pivot 11", with the result that the basket aforesaid is 20 caused to rock forwardly on said pivot; and when said foot shall have relinquished its engagement with said cam-face, said basket, by reason of its own gravity, and by reason of its fulcrum, or axis of movement, being 25 situated forwardly of its center of gravity, returns automatically to its normal, upright position within the stirrup 8'. Hence, any dish contained within said basket will, under the forwardly rocked condition 30 thereof, move outwardly therefrom, by a sliding or rolling motion, depending on the general contour of such dish, along the interior surface or surfaces of said basket with which the dish contacts when placed therein, 35 and enters any appropriate receptacle, as the trough 15; or, said dish, thus delivered from said basket, may be otherwise taken care of, as the user may elect.

To facilitate the delivery of the dish, as 40 above described, the basket aforesaid is provided with a delivery tongue 10", which may constitute an extension of the bottom thereof.

To prevent binding of the deeper dishes, 45 as cups, bowls, and the like, between the back 8" and the wall 9", I provide the basket aforesaid with an interior ledge 15', which may be formed by suitably cutting the back 8", or front wall 9", and bending 50 the material thereof inwardly, said ledge being preferably bowed somewhat downwardly. I also prefer to provide duplicate ledges 15', at the back 8" and front wall 9", interiorly of the basket, so that 55 dishes of medium depth, as cups may engage and slide or roll along both of said ledges, without any binding tendency between the same and said back and said front wall, while still deeper dishes, as bowls, may correspondingly engage and move along either 60 of said ledges, when the basket is tilted as stated. Shallow dishes, as plates, saucers, and the like, may rest directly upon, and correspondingly move along, the bottom of

said basket, under like conditions, all as indicated by dotted lines in Fig. 6.

It will be understood that any appropriate number of the dish-containers aforesaid may be pivotally attached to the conveyer aforesaid, and thereby serially carried into and out of the bath of cleansing fluid contained with in the tank 2.

It is desirable, however, that there be provided, at a suitable point along the course of movement of the conveyer within 75 the bath of cleansing fluid, means for agitating said cleansing fluid, and causing the same to forcibly surge through said dish-container, attached to said conveyer, and hence forcibly impinge against any dish 80 contained in said dish-container. Accordingly, I provide a rotatable dasher 16, preferably of the general form of a screw-propeller, the same being firmly mounted on an arbor 16', rotating in a stuffing-box 16", 85 arranged at the adjacent side-wall of the tank 2, said arbor, hence, projecting outwardly and somewhat beyond said side-wall, to admit of the mounting thereon of a pulley 17, which is in belt connection, as 90 through the medium of a belt 17', with a pulley 17", fast on the main shaft 5, the diameters of the pulleys 17, 17", being such that when said shaft is rotated at a given rate of speed, the arbor 16', and hence the 95 dasher 16, will turn at a much greater speed.

The dasher 16 is situated within the tank 2, and so that the conveyer aforesaid, with the dish-container or dish-containers attached thereto, traverse the direct-acting 100 face thereof; and for further agitating the cleansing fluid, I purpose to make use of an additional dasher 18, mounted on an arbor 18', working in a stuffing-box 18", said arbor 18' carrying a pulley 19, in belt connection with a pulley 19', also fast on shaft 5, the arbor, pulleys and belt last referred to being, respectively, duplicates of the corresponding parts hereinbefore mentioned as 105 being arranged between the shaft 5 and the dasher 16, and relatively disposed accordingly.

The arbors 16', 18', are arranged in axial alinement, and the direct-acting faces of the dashers carried thereby, are presented each 115 toward the other, whereby each dasher, in operation, dashes the cleansing fluid in the direction of the other; and the conveyer moves along a course extending between said dashers, and hence traverses the direct-acting face of each. Accordingly, in the practical operation of the machine as a 120 whole, the cleansing fluid is dashed simultaneously in opposite directions against and through any dish-container, or dish-containers, carried by said conveyer, with the results that a corresponding application of the cleansing fluid is had on any dish contained 125

in any dish-container traversing the direct-acting faces of said dashers, the opposite sides or faces of said dish being accordingly cleansed at a single operation.

To enhance the efficiency of the dashers aforesigned, I purpose to provide the same with shields 19", 19", respectively, said shields being attached, respectively, to the opposite sides of the tank 2, interiorly thereof, and so as to house, each the upper portion of the dasher with which it co-operates.

It is desirable that means be provided for checking any tendency to pendulous action on the part of any dish-container attached pivotally to the conveyer aforesigned, as the same enters and moves along the bath of cleansing fluid immediately agitated by the dashers 16, 18; and with a view to the attainment of this end, I purpose to make use of a guide conforming in all essential details to the guide hereinbefore referred to as being located within and at the rear end of the tank 2, or the dumping station along the circuit traversed by said conveyer.

The guide now under consideration comprises suitably-spaced, longitudinally-channeled, upright members 20, 20', corresponding to the upright members 12, 12", respectively, save that the cam-face 14" is omitted from the member 20'. The guide members 20, 20', are held in position, respectively, by means of suitable braces 21, attached thereto and extended and attached to the adjacent side-walls of the tank 2; and each dish-container, attached to said conveyer, co-operates with said members 20, 20', so far as the guide constituted thereby performs its function of preventing pendulous movement on the part of said dish-container, in the same manner as it co-operates with the guide aforesigned located at the dumping station along the circuit traversed by said conveyer. It will be understood that the circuit traversed by the conveyer may be widely varied to suit the needs or requirements of the user, and further that the dumping station aforesigned may be located at any desired point along said circuit.

In practice, the driving parts of the machine having been set in motion, the conveyer continuously moves on its respective systems of sprocket-wheels, and along a suitable circuit prescribed therefor, thereby carrying any dish-container attached thereto into the cleansing bath, preferably within the compartment 2", and between and hence opposite the direct-acting face of each of the dashers situated therein; thence out of said bath, and preferably into the rinsing bath contained in the compartment 2"'; thence out of said rinsing bath to the dumping station aforesigned, where the basket of said

container is rocked forwardly as hereinbefore described, to allow any dish contained in said dish-container to move outwardly therefrom; and thence along a suitable course to, and again into the washing bath, a dish to be cleansed being placed in each empty container, by an attendant, as said container moves along the circuit of the conveyer above the tank 2.

It will be seen that my improved dish-washing machine is particularly well adapted for the purposes for which it is intended, and further that the same may be modified to a considerable extent, particularly as regards the specific character of the guide or guides made use of for preventing pendulous movement as hereinbefore specified on the part of any dish-container or dish-containers attached to the conveyer, the specific character of each of the dish-containers made use of, it being primarily essential that the same shall be pivotally attached to the dish-carrier, and desirable that the same shall comprise a rocking basket, and various minor details of the general construction, without materially departing from the spirit and principle of my invention.

I claim:

1. A dish-washing machine comprising a tank; a dish-conveyer, movable relatively thereto; a dish-container, pivotally attached to said dish-conveyer, and depending, by its own gravity and at all times, therefrom; and means for temporarily restraining said dish-container against pendulous movement relatively to its said point of pivotal connection with said dish-conveyer, said means being situated at a suitable point along the course of movement of the latter.

2. A dish-washing machine comprising a tank; a dish-conveyer, movable relatively thereto; a frame pivotally attached to said dish-conveyer and depending, by its own gravity and at all times, therefrom; a dish-basket mounted rockably on said frame; means for temporarily restraining said frame against pendulous movement relatively to its said point of pivotal connection with said dish-conveyer, said means being situated at a suitable point along the course of movement of the latter; and means for rocking said dish-basket, while said frame is being temporarily restrained as stated, and in a manner to cause the delivery, automatically, therefrom of any article contained therein.

3. A dish-washing machine comprising a tank, having a rotatable agitator therein; a dish-conveyer, whose course of movement lies partially within said tank, forwardly of said agitator; a dish-container, pivotally attached to said dish-conveyer and depending, by its own gravity and at all times, therefrom; and means for restraining said

dish-container, while passing said agitator, against pendulous movement relatively to its said point of pivotal connection with the dish-conveyer aforesaid.

5. 4. A dish-washing machine comprising a tank, having suitably spaced, rotatable agitators operating oppositely therein; a dish-conveyer, whose course of movement lies partially within said tank, between said agitators; a dish-container, pivotally attached to said dish-conveyer and depending, by its own gravity and at all times, therefrom; and means for restraining said dish-container, while passing between said agitators, 10 against pendulous movement relatively to its said point of pivotal connection with the dish-conveyer aforesaid.

5. A dish-washing machine comprising a tank, having a rotatable agitator therein; a dish-conveyer, whose course of movement lies partially within said tank, forwardly of said agitator; a dish-container, pivotally attached to said dish-conveyer and depending, by its own gravity and at all times, therefrom; and an elongated guide, the latter disposed vertically within the tank aforesaid, engageable by said dish-container in its travel with said dish-conveyer, and serving, accordingly, to restrain said dish-container, 25 while passing said agitator, against pendulous movement relatively to its said point of pivotal connection with the dish-conveyer aforesaid.

6. A dish-washing machine comprising a tank; a dish-conveyer movable relatively thereto; a frame pivotally attached to said dish-conveyer and depending, by its own gravity and at all times, therefrom, said frame having a dish-basket mounted rockably thereon, and being provided with a guide-arm curved concentrically to the axis of the rocking movement of, and slidably engaged by, said dish-basket; means for temporarily restraining said frame against pendulous movement relatively to its said point of pivotal connection with the dish-conveyer aforesaid; and means for rocking said dish-basket, while said frame is being temporarily restrained as stated, and in 40 a manner to cause the delivery, automatically, therefrom, of any article contained therein.

7. A dish-washing machine comprising a tank; a dish-conveyer movable relatively thereto; a frame pivotally attached to said dish-conveyer and depending, by its own gravity and at all times, therefrom; said frame having a dish-basket mounted rockably thereon means for temporarily restraining said frame against pendulous movement relatively to its said point of pivotal connection with the dish-conveyer aforesaid; and a duly-positioned cam, said dish-basket affording a member for engaging said cam,

while said frame is being temporarily restrained, as stated, and whereby a rocking movement is imparted to said dish-basket, and in a manner to cause the delivery, automatically, therefrom, of any article contained therein.

8. A dish-washing machine comprising a tank; a dish-conveyer movable relatively thereto, and consisting of suitably-spaced, endless sprocket-chains, operating in parallelism, and sprocket-wheels for supporting said chains, respectively; a frame, situated between said chains, pivotally attached thereto, respectively, and depending, by its own gravity and at all times, therefrom; a dish-basket, mounted rockably on said frame; and a guide, the latter consisting of opposite, upright members, between which said frame passes and engages, respectively, in its travel with said dish-conveyer, and being thereby temporarily restrained against pendulous movement relatively to its said point of pivotal connection with either of said chains, and one of said members being provided with a cam, said dish-basket affording a part for engaging said cam, 90 while said frame is being restrained as stated, and whereby a rocking movement is imparted to said dish-basket in a manner to cause the delivery, automatically, therefrom, of any article contained therein.

9. A dish-washing machine comprising a tank; a dish-conveyer, movable relatively thereto; a frame pivotally attached to said dish-conveyer and depending, by its own gravity and at all times, therefrom; a dish-basket mounted rockably on said frame; and opposite, longitudinally-channelled guide-members, suitably disposed and between which said frame, with the dish-basket aforesaid thereon, passes, said frame and said dish-basket being provided, the one with a roller adapted to enter and move along the channel of one of said guide-members, and the other with a roller adapted to enter and move along the channel of the other of said guide-members, upon the dish-conveyer aforesaid being duly moved.

10. A dish-washing machine comprising a tank; a dish-conveyer, movable relatively thereto; a frame pivotally attached to said dish-conveyer and depending, by its own gravity and at all times, therefrom; a dish-basket mounted rockably on said frame; opposite, longitudinally-channelled guide-members, suitably disposed, and between which said frame, with the dish-basket aforesaid thereon, passes, said frame and said dish-basket being provided, the one with a roller adapted to enter and move along the channel of one of said guide-members, and the other with a roller adapted to enter and move along the channel of the other of said guide-members; and a cam-

face, the latter situated within the line of travel of the roller on said dish-basket, along the guide-member provided to co-operate therewith, and whereby, under 5 movement duly imparted to said dish-conveyer, said dish-basket is caused to rock in a manner to cause the delivery, automatically, therefrom, of any article contained therein.

FRANK W. BEARDSLEY.
